EMILE HENRI ARQUEMBOURG, OF PARIS, FRANCE, ASSIGNOR TO SOCIÉTÉ JULES GROUVELLE, H. ARQUEMBOURG & CIE., OF PARIS, FRANCE.

CARBURETER.

1,173,762.

Specification of Letters Patent. Patented Feb. 29, 1916.

Application filed July 9, 1912. Serial No. 708,427.

To all whom it may concern:

Be it known that I, EMILE HENRI ARQUEMBOURG, of 71 Rue du Moulin Vert, in the city of Paris, Republic of France, engineer, have invented an Improvement in Carbureters for Explosion-Motors, of which the following is a full, clear, and exact description.

This invention has for its object an improvement in carbureters for explosion motors and particularly to carbureters with automatic air intake, for the purpose of allowing said carbureters to give a constant carburation at any speeds of the motor 15 whether running light or under a load.

In the usual carbureters, it is generally noticed that the spraying nozzle, devised for giving the best running at a high speed under a load, offers a too large cross section 20 of outflow for allowing a good middle running and especially a regular working in case of the motor running light or at a very reduced speed.

The present improvement remedies this 25 inconvenience and consists in the use of a special regulating device proportioning to the power of the motor the cross section of outflow of the gasolene arriving at the spraying nozzle. This regulating device is essentially characterized by a needle valve capable of entering to a greater or less extent into an orifice interposed in the path of the gasolene, between the constant level tank and the spraying nozzle, and actuated either mechanically through the throttle cock, or pneumatically through the medium of a piston actuated by the differences of depression which are produced in the mixing chamber or between the latter and the motor.

40 The accompanying drawings show by way of example several methods of putting the present invention into practice.

Figures 1 and 2 illustrate in vertical section and in end elevation respectively a carbureter provided with the present regulating device with mechanical control of the needle valve. Figs. 3 and 4 illustrate diagrammatically two forms of realization of the pneumatic operating device for actuating the needle valve.

In the form of carbureter illustrated in Fig. 1 *a* designates the constant level tank, *b* is the spraying nozzle, *c* the biconical mixing chamber, *d* the automatic air intake provided with balls, *e* the throttle cock for re-

tarding the outflow. In the path of the gasolene, between the constant level tank *a* and the spraying nozzle *b*, is provided a cavity *f* inclosing a tubular body *g*, terminated at its upper part by a conical head 60 pressing, under the action of a returning spring *h*, against a shoulder *i* on the wall of the cavity *f*. This returning spring *h* takes a bearing in a screw threaded plug *j*. By means of this method of fitting up the parts, 65 the tubular body *g* may be easily removed and substituted for another; thus it is always possible, by the simple substitution of this member *g*, to adjust the diameter of the outlet port for the gasolene to the type of 70 motor to which the carbureter is to be fitted. In the conical head of this tubular body *g* is provided an orifice *g*¹ through which passes the gasolene coming from the constant level tank *a*; moreover, the said tubular body *g* 75 is perforated with ports *g*², allowing the gasolene which has passed through the orifice *g*¹ to flow to the spraying nozzle *b*. Opposite this orifice *g*¹ is mounted a vertically 80 movable needle valve *k* capable of entering to a greater or less extent into said orifice. The maximum opening of the orifice *g* sensibly corresponds to the best running at high 85 speed under a load, that is to say to the case in which the automatic air intake is entirely open and in which the depression in the mixing chamber *c* is sufficient for insuring a proper atomization while remaining as low as possible. On the contrary for running at the lowest speed, in which the automatic air intake is entirely closed, the needle valve *k* is engaged into the orifice *g*¹, so as to 90 considerably diminish the cross section of passage of the gasolene; in this case, the depression in the carbureter, although being 95 low, must, however, be sufficiently high for overcoming the resistances due to capillary action and insuring a continuous spraying of the gasolene. The needle valve *k* may be operated either mechanically or pneu- 100 matically.

In the mechanical operating device illustrated in Figs. 1 and 2, the needle valve *k* is urged upwardly by a returning spring *l* and its upper end is constantly held in contact, by the action of this spring, against an abutment screw *m* carried by an arm *n* secured on a shaft *o* on the end of which is rigidly mounted a lever *p* the end of which fits against a cam *g* of suitable shape mount- 105 110

ed on the axis e^1 of the throttle cock e . By operating the abutment screw m , it is possible to effect the initial adjustment of the suitable penetration of the end of the needle k into the orifice g^1 , corresponding to the running at a reduced speed.

Figs. 3 and 4 illustrate two methods of realization of the pneumatic operating device for actuating the needle valve k . In 10 these two devices, the needle k is secured to the small arm of a bell crank r movable about an axis s the long arm of which is on the one hand urged by a returning spring t and on the other hand is connected to a 15 piston u movable within a cylinder v communicating either with the mixing chamber c (Fig. 3) or with conduit pipe w beyond the throttle cock e (Fig. 4). The variations of depression either in the mixing chamber 20 c or in the conduit pipe w , produced by the differences of speed of the motor, have for effect to determine a displacement of the piston u in one direction or the other, which displacement imparts, through the medium 25 of the bell crank r , an upward or a downward movement to the needle k which thus closes to a greater or less extent the orifice g^1 . The respective positions of the piston u and of the spring t relatively to the bell 30 crank r are reversed, as illustrated in Figs. 3 and 4, considering that the depression in the mixing chamber c and in the conduit pipe w vary in reverse direction, but always in a progressive manner.

35 It is to be understood that the methods of realization indicated above are given only by way of example and that they may be modified according to the different types of carbureters.

40 Claims:

1. In a carbureter for explosion motors, in combination with a constant level tank and a spraying nozzle, a device for regulating the cross-section of outflow of the gasoline proportionally to the power of the motor, comprising an accessible cavity provided in the path of the gasoline between the constant level tank and the spraying

50 nozzle,—a removable tubular member in said cavity provided at its upper part with a conical head perforated with a central hole for the passage of the gasoline coming from the constant level tank, and side orifices formed opposite the conduit-pipe leading to the spraying nozzle,—a coil spring pressing the conical head of said tubular member against a shoulder on the wall of the cavity containing this tubular member,—a screw-threaded plug closing said cavity and serving as a bearing for the coil spring,—a 55 needle valve capable of being engaged to a greater or less extent into the central hole of the conical head of the tubular member,—and means for moving the needle valve and imparting to it displacements proportional to the power to be given by the motor.

2. In a carbureter, the combination with a tank, and a spraying nozzle, a cavity being arranged between the tank and nozzle, of a removable tubular member in the cavity 70 and having an aperture in its inner end and lateral apertures, a plug closing the cavity, means for holding the apertured inner end of the member against the shoulder of the cavity, and a needle valve engaging the 75 aperture in the inner end of the said member.

3. In a carbureter, the combination with a tank, and a spraying nozzle, a cavity being arranged between the tank and nozzle, of a removable member in the cavity and having its inner end provided with an opening through which the liquid from the tank passes to the nozzle, a closure for the cavity, means for holding the member in engagement with the shoulder at the inner end of the cavity, and a needle valve engaging the opening of the said member.

The foregoing specification of my improvement in carbureters for explosion motors, signed by me this twenty-second day of June, 1912.

EMILE HENRI ARQUEMBOURG.
